RAILWAY CAR

William E. Wine, Toledo, Ohio

Application August 1, 1934, Serial No. 737,973

7 Claims. (Cl. 105—414)

My invention relates to railway cars and more particularly to improvements in the end construction thereof, which includes the body bolster.

The principal object of the invention is to provide improved means for rigidifying a railway car, principally the ends thereof, against draft and buffing forces.

Another object of the invention is to provide a body bolster with means particularly adapted to resist buffing and draft forces and to also effectively resist overturning moments induced by these forces.

A primary feature of the invention consists in providing a railway car with diagonal braces which extend inwardly from the corners of the car and are rigidly secured to the center sill intermediate the top thereof and a portion of the body bolster which overlies the center sill.

Another feature of the invention consists in providing a body bolster of truss form with truss members which integrally connect the tension and compression members thereof and diverge downwardly on opposite sides of the center sill, the truss members being respectively connected to the tension member at points in substantial vertical alignment with the sides of the center sill and the compression members extending upwardly from points adjacent the lower ends of the truss members and merging with the tension member adjacent the outer ends thereof.

A further feature of the invention consists in providing a body bolster of truss form having compression members which merge with the tension member at the ends of the latter with downwardly depending portions for attachment to the side sills of the car.

Another feature of the invention consists in providing the body bolster with a lower plate member which is formed with an upstanding transversely extending hollow casting rigidifying the bolster at the portions thereof cooperable with the side bearings of the car and affording convenient means for uniting the diagonally extending members of the bolster with the plate portion.

Other and more specific features of the invention, residing in advantageous forms, combinations and relations of parts, will hereinafter appear and be pointed out in the claims.

Referring to the drawings, illustrating a preferred embodiment of the invention,

Figure 1 is a top plan view of the portion of a railway hopper car adjacent one of the body bolsters, parts of the floor sheets of the car being broken away.

Figure 2 is a side elevational view of the body bolster and associated parts of the car as seen looking toward the center of the car.

Figure 3 is a plan view, partly in elevation and partly in section, the floor sheets being removed, of one of the end portions of the car.

Figure 4 is an enlarged end view of the body bolster.

Figure 5 is an enlarged sectional view taken on line 5—5 of Figure 2, the center sill being omitted.

Figures 6, 7, 8 and 9 are enlarged detail sectional views taken respectively on lines 6—6, 7—7, 8—8 and 9—9 of Figure 2, the bottom cover plate being omitted in Figures 6 and 8.

Figure 10 is an enlarged side elevational view of the central portion of the body bolster.

Figure 11 is a sectional view taken on line 11—11 of Figure 10.

While a railway car of the hopper type has been chosen for illustrating the invention, it will be appreciated as the specification proceeds and particularly by those skilled in the art that many features of the invention may apply with equal facility and effectiveness to cars of other types, such, for instance, as those customarily referred to as gondola cars.

Referring more particularly to the drawings, 1 indicates the car center sill, which, as shown, may advantageously be formed as a unitary member comprising a top wall 2 and downwardly extending side walls 3 which terminate in laterally projecting flanges 4. Paralleling the center sill along opposite sides of the car are the side sills 5 which may be conveniently of angle shape to provide a substantially vertical plate portion 6 and a substantially horizontal inwardly projecting plate portion 7. At their ends, the side sills are rigidly connected to each other and to the center sill by end sills 8 which may also be of angle shape to provide plate portions 9 and 10 respectively corresponding to the vertical and horizontal plate portions 6 and 7 of the side sills.

The body bolster, generally designated by the reference numeral 11, is of truss form and may conveniently be cast as a unitary structure. The bolster includes a tension member 12 extending continuously from one side of the car to the other in spaced relation to the top of the center sill and compression members 13 which extend outwardly from opposite sides of the center sill. The tension member is formed with an inclined top flange or plate portion 14 underlying and rigidly secured to the inclined floor sheets 15 of the car and with

a downwardly extending plate portion 16 which inclines rearwardly from the forward edge of the top plate 14 and terminates in a substantially vertical plate portion 17 forming with other parts 5 of the body bolster a centrally disposed web. The top plate 14 may, if desired, be formed with rearwardly extending projections 17 which underlie and thus support the forward ends of angularly-shaped members 19, which extend beneath and 10 rigidify the portion of the car floor between the body bolster and the adjacent end of the car, portions of these members being illustrated in Figure 5. The compression members 13 have substantially horizontally extending portions 20, 15 each of which is formed with a bottom plate member 21 and an upwardly projecting flange 22 which constitutes a part of the centrally disposed web of the bolster. Adjacent their inner ends, the bottom plate members 21 overlap and are rigidly 20 secured to the laterally projecting flanges 4 of the center sill and they are provided with upwardly projecting extensions 23 for attachment to the side walls 3 of the center sill. The side bearings 25 of the car (not shown) are adapted to cooperate with the outer end portions of the plate members 21 and, at these points, they are preferably enlarged laterally, as indicated at 24.

The tension and compression members are integrally united by truss members 25 which 30 diverge downwardly on opposite sides of the center sill from the tension member at points in substantial vertical alignment with the side walls of the center sill, being joined with the compression members 13 at the portions thereof which are co-operable with the side bearings of the car. From these portions, the compression members extend upwardly and merge with the tension member adjacent the outer ends thereof. The upwardly inclined portions of the compression members, 35 designated by the numeral 26, together with the truss members 25, are of substantially cruciform shape in cross section, the truss members having plate portions 27 and 28 and the upwardly extending portions of the compression member having plate portions 29 and 30. The plate portions 27 and 29 of the truss and compression members respectively form a part of the central web of the bolster and the outer edges of the plate 40 portions 30 are preferably formed with flanges or ribs 31 which serve to additionally rigidify the bolster against transverse bending strains caused by buffing and draft forces.

The portions 24 of the bottom plate member 55 21 of the bolster are integrally formed with upwardly projecting transversely extending hollow members 33. These members serve to rigidify the bolster at the portions which cooperate with the side bearings of the car and, in addition to this desirable function, they serve to join the plate 60 portions 28 and 30 of the truss members 25 and the upwardly inclined portions of the compression members to the bottom plate 21 of the bolster. By connecting these plate portions to the plate member 21 in this fashion, concentration of a 65 relatively large solid mass of metal at the points where these members of the bolster would otherwise intersect is prevented, thus the possibility of the bolster being weakened at these points, due to shrinkage cracks, is practically entirely eliminated. On opposite sides of the central web of the bolster, the members 33 are formed with 70 openings 33a for receiving a suitable tool to rivet the bottom cover plate 21a to the underside of the bottom plate 21 of the bolster, the bottom

cover plate, in addition to being secured to the bolster at a number of points along the bottom plate 21, being also secured to the laterally projecting flanges 4 of the center sill. While the members 33 are shown as being substantially 5 semi-cylindrical in cross section, those skilled in the art will appreciate that the results obtained by providing the bolster with such members may be as effectively produced by hollow members of other cross sectional shapes. 10

Adjacent its outer ends, the body bolster is formed with rigid members 34 which depend from the outer ends of the compression members 13 for attachment to the side sills of the car and to provide the bolster with extended areas to which 15 adjoining side stakes 35 of the car may be secured. Each of these members is formed with an end flange 36 secured to the vertical plate portion 6 of the adjacent side sill, with a bottom flange 37 secured to the horizontal plate portion 20 of the side sill and with a vertical portion 38 which constitutes a continuation of the central web of the bolster. The side stakes 35, which are disposed within the car body, are of angular 25 shape, having a flange 39 to which the side sheets of the car are secured and a flange 40 which is secured to the outer end portions of the web of the bolster and the vertical portions 38 of the depending members 34. Like the depending members 34, the side stakes 35 are formed with bottom 30 flanges 41 which are secured to the horizontal plate portions 7 of the side sills and, together with the bottom flanges 37, afford portions for cooperating with jacks or the like to elevate the body 35 of the car relatively to the car trucks. 35

To prevent lading becoming entrapped behind the side stakes 35, the portions of the top flange 14 of the tension member of the bolster which extend from the inner edges of the stakes to the 40 car sides are inclined upwardly, as at 42, so as to lie in planes substantially parallel with the longitudinal axis of the car and the portions of the floor sheets of the car overlying these portions of the bolster are similarly inclined, as indicated at 43 in Figure 1. To support the portions of the 45 floor sheets of the car adjoining the front face of the side stakes and to also close the openings cut in the floor sheets to receive the side stakes, the latter may be integrally formed with lugs or 50 projections 44, the upper surfaces of which are inclined to lie in planes substantially parallel with the plane of the floor.

Depending downwardly from the tension member at the points where the truss members 25 respectively intersect it are rigid members 45, 55 each of which comprises a substantially triangularly shaped plate portion 46 extending transversely of the bolster and a laterally projecting flange or the like 47 which forms a part of the 60 central web of the bolster. At their lower ends, the members 45 are integrally connected by a substantially horizontal plate portion 48 which overlies and is rigidly secured to the top of the center sill. This plate portion, together with the 65 members 45, projects a relatively great distance from the bolster toward the center of the car, thus serving to effectively resist overturning tendencies of the bolster caused by buffing and draft forces. Moreover, these members, since they project a relatively great distance toward the center 70 of the car in overlapping relation to the top of the center sill, function to reinforce the center sill against upward movement adjacent the inner 75

side of the bolster, which movement has been found to result from severe buffing forces.

In addition to being connected by the horizontal plate portion 46, the members 45 may be also joined adjacent their upper ends by a central web 49 and at their lower ends by a web 50 and also by a wall portion 51, which is formed integrally with reinforcing flanges 52 projecting inwardly from the marginal edges of the plate portions 46. By connecting the members 45 in this manner, it will be appreciated that they, in effect, form one rigid member having plate portions which extend downwardly from the tension member at points adjacent the upper edges of the truss members 25.

Extending diagonally inwardly from the corners of the car are braces 53 having a longitudinally extending reinforcing corrugation 54, which inwardly of the ends of the braces merge into the body portion thereof to provide plate-like end portions 55 and 56. Each of the outer end portions 55 of the braces is secured to a gusset plate 57, which, in turn, is connected by rivets to the upper side of the horizontal plate portion 7 of the side sill and to the under side of the horizontal plate portion 10 of the end sill, the brace being interposed between the gusset and the horizontal portion of the end sill and being connected to the latter and the horizontal portion of the side sill by many of the rivets which connect the gusset to those parts of the sills. By connecting the braces to the sills in this manner, it will be perceived that an extremely rigid construction is produced, as many of the connecting rivets are in double shear. The plate portions 56 at the inner ends of the braces are disposed closely adjacent each other and are interposed between the top of the center sill and the horizontal plate portion 48 of the body bolster, being secured to the center sill by many of the rivets employed for connecting the plate 48 thereto and by additional rivets 58 which are disposed within an opening 59 in the plate portion. If desired, the plate 48 may be offset upwardly, as indicated at 60, for receiving the end portions 46 of the braces. This manner of connecting the diagonal braces to the center sill results in rigidifying the ends of the car underframe to a much greater extent than has heretofore been considered possible. The strength of the connection between the braces and center sill is not dependent, as has been the case in the past, upon a bracket which is customarily secured to the center sill and sometimes to the bolster as well and, moreover, the braces 55 may be disposed at a less angle to the center sill, which is, obviously, desirable, since it is possible for them to extend onto the other side of the bolster.

What I claim is:

1. In a railway car, the combination with a center sill, of diagonal braces extending inwardly from the corners of the car and having portions disposed in overlapping relation to the top of the center sill, a body bolster having a rigid portion disposed in overlapping relation to said por-

tions of the braces, and means passing through the latter for connecting the braces directly to the body bolster and center sill.

2. In a railway car, the combination with a center sill, of an end sill, side sills secured to the end sill, a body bolster having a portion overlying and rigidly secured to the top of the center sill, and braces extending diagonally inward from adjacent the points of connection of the end and side sills and rigidly secured to the top of the center sill between the latter and said portion of the bolster.

3. In a railway hopper car, the combination with a center sill, of an end sill, side sills secured to the end sill, of a body bolster involving a tension member disposed above the center sill, said bolster being provided with rigid means extending downwardly from the tension member and rigidly secured to the top of the center sill, and braces extending diagonally inward from adjacent the points of connection of the end and side sills and having portions interposed between the top of the center sill and said downwardly extending means of the bolster, said portions of the braces being rigidly secured to the center sill.

4. A railway car having a cast metal transversely extending load carrying member of truss form provided with top and bottom plate members, diagonal members integrally connecting said plate members and respectively having plate portions disposed in planes intersecting each other in a line adjacent to and substantially parallel with one of said plate members, said last named plate member being integrally formed with a laterally offset transversely extending hollow member uniting said plate portions to said plate member.

5. A railway car having a cast metal transverse load carrying member of truss form provided with top and bottom plate members, one of said members having a laterally offset transversely extending hollow member, and diagonal members connecting said plate members and respectively having plate portions angularly disposed with respect to each other and integrally joined to said hollow member at spaced points.

6. A railway car body bolster having a bottom plate member provided with portions adapted to cooperate with the side bearings of the car, each of said portions being provided with an upwardly projecting transversely extending hollow reinforcing member.

7. A railway car body bolster of truss form having a bottom plate member provided with portions adapted to cooperate with the side bearings of the car, each of said portions having an upwardly projecting transversely extending reinforcing member, the side edges of each reinforcing member being integral with the plate member and portions thereof intermediate its side edges being spaced from the plate member, said body bolster also having truss members integrally connected to said reinforcing members intermediate the side edges thereof.

WILLIAM E. WINE. 65
